UNITED STATES PATENT OFFICE.

GEORGE B. CARTER AND JAMES R. CARTER, OF PETERSBURG, VIRGINIA.

VENDING-MACHINE.

SPECIFICATION forming part of Letters Patent No. 663,258, dated December 4, 1900.

Application filed May 10, 1900. Serial No. 16,130. (No model.)

To all whom it may concern:

Be it known that we, GEORGE B. CARTER and JAMES R. CARTER, citizens of the United States, residing at Petersburg, in the county 5 of Dinwiddie and State of Virginia, have invented certain new and useful Improvements in Vending-Machines; and we do hereby declare the following to be a full, clear, and exact description of the invention, such as will 10 enable others skilled in the art to which it appertains to make and use the same.

Our invention relates to automatic vending-machines, particularly of the nickel-in-the-slot type; and it has for its prime object 15 the vending of cigarettes in packages, although it will be obvious that the mechanism is capable of delivering a variety of packages or other articles.

Another object of the invention is to provide 20 a prepaid delivery mechanism of the simplest and cheapest form, effective in operation, and durable in all of its parts.

Still another object is to provide for the 25 chance delivery of a "prize-ticket."

Other objects will become apparent upon 30 further description of the invention.

The invention consists of the novel construction, arrangement, and combination of the several mechanisms comprising the apparatus, as will be hereinafter more fully described, and particularly stated in the claims.

In the accompanying drawings, Figure 1 is 35 a front elevation of the apparatus, the case being partly in section and partly broken away to show the mechanism; Fig. 2, a top plan view of the mechanism removed from the case; Fig. 3, a rear side elevation of the mechanism; Fig. 4, a vertical longitudinal section of the package-delivery mechanism 40 and the prize-ticket mechanism, showing the case in dotted lines; Fig. 5, an end elevation showing a portion of the base or support broken away; Fig. 6, a similar view of the opposite end, and Fig. 7 a detail of a portion 45 of the prize-ticket-delivery mechanism.

In order to more readily understand the construction and operation of the device, we will describe the several mechanisms under the following heads, viz: the case, the push- 50 rod and coin locking mechanism; the article-ejector mechanism, the coin-raceway, and the prize-ticket-delivery mechanism.

The case.—The case 1 may be constructed of any suitable material and may be of any

desired shape, preferably of the shape outlined in the drawings, wherein the lower portion, which is designed to receive and hold the mechanism, is of a greater width than the upper portion.

The front of the case is provided with a sight-opening 2, opposite the package-containing compartment, and with a package-delivery chute 3 and a prize-ticket-delivery chute 4.

One end of the case is provided with a door 5, through which the mechanism and its supporting-base are entered and taken out.

The push-rod and coin locking mechanism.—Mounted upon a suitable base 6, preferably consisting of a frame composed of end pieces 7 7, top piece 8, bottom piece 9, and a front piece 10, the top being of less width than that of the frame, are two vertical brackets 11 and 12. Mounted in these brackets is a spring-actuated push-rod 13, the outer portion of which is cylindrical in cross-section and has its end which projects through an opening in the door provided with a knob 14. Mounted on the push-rod between the brackets is a sleeve 19, provided with a coin-slot 21, which registers with a slot 22 in the push-rod. The sleeve is provided with a flange 23, by means of which it is secured to a reciprocating bar 24, provided with a cam edge 25. The bar 24 reciprocates in suitable guide-slots in the brackets 11 and 12 and is provided with a shoulder 27 to limit its inward movement.

The push-rod is provided with a lug or stud 28 to limit its outward movement by striking 90 against the bracket 11, and the outward movement of the bar 24 is limited by the sleeve 19 contacting with the bracket 12. Attached to the bracket 12 is a hub 29, which is provided with a slot 30, into which projects an arm 31 95 of the spring-actuated dog 32, pivoted to the bracket below the hub.

The push-rod is provided with a cut-away portion 33, into which the arm 31 is forced by the action of the spring when the push-rod 100 is forced inward, and the edge of the reciprocating bar is provided with a slight recess 34, into which the lower arm 35 of the dog enters to momentarily lock the push-rod and reciprocating bar together, so as to allow the coin 105 sufficient time to drop through the slots in said push-rod and reciprocating bar.

The article-ejector mechanism.—The nu-

meral 36 indicates a plate having a vertical stud 37, on which is fulcrumed a lever 38. One end of this lever carries a friction-wheel 39, adapted to bear against the cam edge of the reciprocating bar, and the other end is preferably provided with a slightly-curved projection 40, adapted to bear against one end of a spring-actuated ejector-rod 41, operating in bearings made in the arms of a bracket 42. The other end of the ejector-rod is attached to an ejector-plate 43, operating in guides 44 44.

The numeral 45 indicates a package-compartment, which is open at the front and has the front edges of its side walls provided with inwardly-projecting flanges 46 46 to retain the articles or packages within the compartment. These flanges do not extend to the floor of the compartment, being cut off a short distance above the floor to leave sufficient space for the delivery of the article, which in the present instance is a package of cigarettes, and the front edge of the floor is beveled, as shown at *a*, to facilitate the delivery of the package.

25 In order to prevent the bottom package from accidentally falling out, two springs 47 47 are provided, one at each side of the compartment. The force exerted by these springs while sufficient to prevent the package falling out is easily overcome by the force exerted upon the ejector-plate when the machine is operated to deliver a package.

30 *The coin-raceway.*—The numeral 48 indicates the coin-raceway, which is detachably connected at one end to the bracket 12, the front of the case being provided with a slot suitable to accommodate the entry of the proper coin into the raceway. The exit-opening 49 of the raceway registers with the slotway in the reciprocating sleeve and the push-rod.

35 *The prize-ticket-delivering mechanism.*—Mounted upon a suitable base 50 is a metal cylinder 51, having one end open and the other end closed by a cap 52. The cylinder is provided with a hopper 53, opening into the cylinder, said hopper being adapted to receive the coin as it falls from the slotway in the reciprocating sleeve and push-rod and through 40 an opening 54 in the top of the base 6. In order to prevent the coin dropping into the hopper with too great frequency, the object being to have the coin drop into the hopper only occasionally—say on an average of once 45 in about fifteen operations of the machine—a vertical plate 55 is secured transversely the mouth thereof. In the under side of the cylinder directly beneath the hopper is an opening 56 for the exit of the coin, and at one side 50 thereof a spring-finger 57 may be secured to prevent the coin from accidentally falling before being released by the return of the push-rod, as will be described later on.

60 The numeral 58 indicates a piston-rod which has its outer end pivoted to one end of a vertical rod 59. This rod passes up through the top of the base and has its upper end se-

cured in the inner end of the push-rod. If desired, the rod 59 may be insulated from the push-rod in order to prevent the package-delivery mechanism from becoming charged with the electric current. Situated within the open end of the cylinder 51 is a cylindrical contact-maker 60, which is restrained in operative position by means of a slot 61 and a set-screw 62. The outer end of the contact-maker is beveled or inclined, as shown at *b*, for gradually operating a spring-restrained ejector-rod 63, journaled in suitable bearings. This rod carries at one end a friction-roller 64, which is in constant contact with the beveled end of the contact-maker and has its other end connected to a vertical rod 65. The rod 65 passes up through the top of the base and has its upper end connected to a ticket-ejector plate 66, which is arranged to reciprocate beneath a ticket-compartment 67, as shown in Fig. 5. The ticket-ejector plate is provided with an opening 68 of sufficient diameter to receive and hold a ticket, which on the outward throw of the ejector-plate will be discharged onto the delivery-chute 4. The inner end of the contact-maker is provided with a head 69, having a perforation through which the end of the piston-rod works, and until a coin passes through the hopper into the cylinder the contact-maker is not set in operation.

65 The numeral 70 indicates an electric bell which is placed in connection with a battery 71, the cylinder 51, and a suitable spring-contact 72.

70 To operate the machine, the proper coin is passed through the slot into the raceway. The coin rolls on its edge down the raceway and falling into the slots in the reciprocating sleeve and push-rod locks said sleeve and rod together. After the coin has been deposited the push-rod is forced inward and as the sleeve is locked to said rod it (the sleeve) and the bar 24 will move together, the cam edge 75 of said bar causing the end of the lever 38 carrying the friction-roller to move outward and the other end 40 to move inward. As the end 40 moves inward the ejector-plate will push the lower or bottom package out through 80 the opening onto the shelf *c*. As the slot in the push-rod is of slightly greater length than the slots in the sleeve, the coin will drop out as soon as the push-rod is released. In dropping, the coin passes through the opening 54 in the top of the base and striking upon the edge of the plate 55 it either bounds to the bottom of the base or falls into the hopper 53. If the coin falls into the hopper, it drops upon the piston-rod 58, and the push-rod being 85 again forced in the coin will be caught between the end of the piston-rod and the contact-maker. The push-rod being released, the piston-rod, moving with the push-rod on its return to normal position, will impinge 90 the coin against the end of the contact-maker, forcing said contact-maker outward against the spring-pressure of the ejector-rod 63 until the contact-maker contacts with the spring- 95

contact 72, when the alarm will sound, indicating that a prize-ticket has been ejected. During the forcible outward movement of the contact - maker the ejector - rod 63 will be forced outward, and as its outer end is connected to the ticket-ejector plate by the rod 65 it will be seen that a ticket will be ejected through the ticket-opening onto the ledge or shelf d. When the push-rod is again forced in, the coin will be released owing to the diminishing pressure of the spring-restrained rod 63 upon the beveled end of the contact-maker as the latter is forced back to its normal position.

15 Various modifications or changes may be made in the construction and arrangement of the various parts of the machine without departing from the spirit of our invention or sacrificing the principle thereof.

20 Having thus fully described our invention, what we claim, and desire to secure by Letters Patent, is—

1. In a vending-machine, the combination of an article-compartment, an article-ejector, a 25 coin-raceway, a spring-actuated slotted push-rod, a slotted sleeve adapted to be locked to the push-rod by a proper coin, carrying a cam-edge bar, and a fulcrumed lever, one end of which is operated by the cam edge of the bar 30 to cause the other end to actuate the article-ejector.

2. In a vending-machine, the combination of an article-compartment, a spring-restrained article-ejector, a coin-raceway, a spring-actuated push-rod provided with a coin-slot, a sleeve mounted on the push-rod, provided with a cam-edge bar and with slots registering with the coin-slot in the push-bar, said push-rod and sleeve adapted to be locked together by a proper coin, and a fulcrumed lever carrying at one end a friction-roller, one end of said lever being operated by a cam edge of the bar to cause the other end to actuate the article-ejector.

45 3. In a vending-machine, the combination of an article-compartment, an article-ejector, a coin - raceway, a spring - actuated push-rod, mounted in suitable brackets, provided with a coin-slot, a sleeve, mounted on the push-rod, provided with a cam-edge bar operating in guides in the brackets, said sleeve provided with slots registering with the coin-slot in said push - bar, the push - bar and sleeve adapted to be locked together by a proper 55 coin, and a fulcrumed lever, as and for the purpose specified.

4. In a vending-machine, the combination with an article-compartment, an article-ejector, a coin-raceway, a spring-actuated push-rod provided with a coin-slot, a sleeve mounted on the push-rod, provided with a cam-edge bar and with registering coin-slots, the push-rod and sleeve adapted to be locked together by a proper coin, and a fulcrumed lever, of a 65 ticket-delivery mechanism.

5. In a vending-machine, the combination with an article-compartment, an article-ejec-

tor, a coin-raceway, a spring-actuated push-rod provided with a coin-slot, a sleeve, mounted on the push-rod, provided with a cam-edge 70 bar and with registering coin-slots, the push-rod and sleeve adapted to be locked together by a proper coin, and a fulcrumed lever, of a ticket-delivery mechanism, an alarm-bell, and suitable electrical connections.

6. In a vending-machine, the combination with a spring-actuated push-rod having a coin-delivery opening, of a ticket-delivery mechanism comprising a suitable cylinder provided with a coin-entrance and a coin-exit, 80 a piston-rod in the cylinder having one end connected to the push-rod, a spring-restrained ejector-rod having one end connected to an ejector-plate, and an independent slideable contact-maker arranged to be moved in one 85 direction by the piston-rod and in the opposite direction by the tension force of the ejector-rod.

7. In a vending-machine, the combination with a spring-actuated push-rod having a 90 coin-slotway, of a ticket-delivery mechanism comprising a suitable cylinder provided with a coin-entrance and a coin-exit, a piston-rod in the cylinder having one end connected to the push-rod, a spring-restrained ejector-rod having one end connected to an ejector-plate and the other end carrying a friction-roller, an 95 independent slideable contact-maker arranged between the piston-rod and ejector-rod, so as to be operated in one direction by said piston-rod and in the opposite direction by said ejector-rod, means for temporarily retarding the exit of the coin, a ticket-compartment having an exit, an alarm-bell and electric connections, whereby an alarm is sounded 105 when a coin is between the piston-rod and contact-maker.

8. In a vending-machine, the combination of a spring-actuated push-rod having a coin-slot, a sleeve mounted on the push-rod, said 110 sleeve being provided with slots adapted to register with the coin-slot in the push-bar, a reciprocating bar attached to the sleeve, and means for temporarily locking the push-rod and reciprocating bar together, so as to allow 115 for the release of the coin.

9. In a vending-machine, the combination of a spring-actuated push-rod having a coin-slot, a sleeve mounted on the push-rod, said 120 sleeve having registering coin-slots, a reciprocating bar carried by the sleeve, said bar being provided with a cam edge, a spring-actuated ejector-rod, and a fulcrumed lever having one end adapted for engagement with the cam edge of the reciprocating bar and the 125 other end with the ejector-rod.

In testimony whereof we affix our signatures in the presence of two witnesses.

GEO. B. CARTER.
JAS. R. CARTER.
